UNITED STATES PATENT OFFICE.

GEORGE C. VANMEER, OF BURK'S FALLS, ONTARIO, CANADA.

SEPARABLE FASTENER.

1,187,571.

Specification of Letters Patent. Patented June 20, 1916.

Application filed April 12, 1915. Serial No. 20,825.

To all whom it may concern:

Be it known that I, GEORGE C. VANMEER, subject of the King of England, residing at Burk's Falls, in the Province of Ontario, 5 Dominion of Canada, have invented certain new and useful Improvements in Separable Fasteners; and I do hereby declare the following to be a full, clear, and exact description of the invention, such as will enable 10 others skilled in the art to which it appertains to make and use the same.

This invention relates to a separable fastener.

An object of the invention resides in the 15 provision of a fastener, the parts of which may be quickly secured together.

A further object of the invention resides in so constructing the device that when the two parts are interengaged they will be automatically locked in such position. 20

A further object of the invention resides in making the fastener so that one of the members will be adjustable within the other.

A still further object of the invention resides in so constructing the device that it 25 will be neat and of such formation as to be particularly adapted for securing the two parts of a rubber or other shoe together.

With these and other objects in view, such 30 as will appear as the description progresses, my invention comprises the combination and arrangement of parts as set forth in and falling within the scope of the appended claim.

35 Referring to the drawing: Figure 1 is a plan view of my device looking at the side on which the spring is located. Fig. 2 is a longitudinal sectional view. Fig. 3 is a side elevation. Fig. 4 is a section on line 4—4 of

40 Fig. 1.

Referring to the drawing wherein like parts are indicated by like characters throughout the several views: In the embodiment of my invention shown in the 45 drawings, I have provided a plate 1 which is curved from end to end and has a loop 2 formed on one end thereof. Extending longitudinally of the plate 1 is a housing 3 which is formed by depressing a portion of the plate. Secured to the plate 1 is a 50 U-shaped spring 4 which is attached, as at 5, and lies in slight spaced relation to the face of the plate. The bight portion 6 of this spring bridges the housing 3 in the manner 55 clearly illustrated in the drawing. The other member of the fastener includes a bar

7 on one end of which is formed a loop 8. Formed on this bar 7, at spaced intervals, are projections 9 which are inclined toward the loop 8. The body portion of the bar 7 60 is of such dimensions that it will lie entirely beneath the plane of the plate 1 and within the housing 3. The upper ends of the projections 9 will extend above the plane of the plate 1. 65

When it is desired to secure the two members of the fastener together it is only necessary to push the bar 7 inwardly into the housing 3 at which time the bight portion 6 of the spring 4 will ride up on the inclined 70 face of each successive projection 9 and will drop in behind the projection. This movement may be continued until the bar 7 has been pushed into the housing 3 to a sufficient extent. It will be thus seen that the bight 75 portion 6 of the spring 4, engaging one of the projections 9 will prevent the disengagement of the members of the fastener without the manual actuation of the spring. The spring, however, will allow the fasteners 80 to be pushed together to any degree and will automatically lock them in such position.

From the foregoing description it will be seen that I have provided a separable fastener which is of very simple construction and yet one which will be exceedingly useful and which is of such construction that the parts are not likely to get out of order. 85 90

While I have illustrated and described a particular embodiment of my invention, I have merely done so for the sake of convenience and I do not wish to be limited to that particular embodiment as it is obvious that 95 numerous changes may be made within the details of construction thereof without in any way departing from the spirit of the invention or without exceeding the scope of the appended claim. 100

What I claim is:—

In a separable fastener, the combination with a plate having a longitudinally extending channel formed by a depressed portion of the plate, of a bar slidably mounted in the channel and having teeth thereon adapted to extend outwardly beyond the face of the plate, the body of the bar being adapted to be located entirely within the channel, and a U-shaped spring detent having its leg portions hinged to the plate and its bight portion bridging the channel and adapted to en- 105 110

gage between the teeth on the bar, the portion of the spring which engages the teeth being smooth and free from projecting parts and having its upper edge adapted to lie flush with the edges of the teeth, the legs of the 5 detent lying in slight spaced relation to the plate throughout their entire length.

In testimony whereof, I affix my signature, in the presence of two witnesses.

GEORGE C. VANMEER.
